FAIRLEADER

Marc D Troyer, Seattle, Wash., assignor to Berger
Engineering Company, Seattle, Wash., a corporation of Washington

Application December 26, 1950, Serial No. 202,739

2 Claims. (Cl. 254—190)

1

This invention relates to fairleaders, and it has reference more particularly to fairleaders as applied to the outer ends of swinging booms as used for the handling of buckets, grapples, shovels, and the like, where two lines or cables are employed and where both cables extend to the bucket or grapple through the fairleader.

It is the principal object of this invention to provide a fairleader through which a "load line" is passed for the lifting of the grapple, bucket or other device being handled, along with a "closing line" for controlling the closing and opening of the grapple; the fairleader housing being rotatably mounted and adapted to automatically adjust its position in its supporting bearing to the direction of pull of the load line, thus to avoid the chafing of the cables on the sides of the fairleader housing.

To impart a better understanding of the advantages of the present invention, it will here be explained that it has become a practise in the sugar cane growing industry, to cut the cane stocks and deposit them in windrows or piles across the fields. The cut material is then loaded onto carts for transportation to places of use. Loading is accomplished by means of large grapples suspended from booms mounted on tractors of the crawler track types. It is a general practise to advance the tractor between two windrows and load from each side. As a load is lifted by the grapple, the boom is swung to a position over the cart and the load released. Then the boom is swung back for another load while the load line and closing line are being paid out. The swinging of the boom from side to side, and the almost continuous running of the lines results in excessive wear thereon by reason of their rubbing on the side walls of the fairleader housing.

Present day fairleaders as used on such booms are fixed in position as distinguished from being of the automatically aligning type. Furthermore, where two lines have been used, they have been passed over sheave wheels set in the housing side by side and on the same axis. Therefore, the cables because of their closeness to each other are subjected to unusual chafing one on the other, as well as on the housing walls. This damage to or wear on lines or cables used as above disclosed in non-adjustable housings, cannot be overcome except by slowing down the operation, and paying out or drawing in the cables only while the boom is at rest.

In view of the above explanatory matter, it has been the principal object of this invention

5 to provide a fairleader of novel form, designed for the use therewith of two lines or cables, and having the cable guide sheaves in tandem and so arranged in the housing that the weight applied to the load line will effect and maintain an automatic alignment of the fairleader housing with the direction of pull of the load supporting cable and thus avoid chafing of the cables on the housing walls and also prevent chafing by rubbing on each other.

10 Specifically stated, the present invention resides in the provision of a fairleader housing with a tubular mounting stem, rotatably contained in a supporting bearing and providing for passage of two cables through the stem and housing; and there being cable guide sheaves in the housings so related to the turning axis of the housing that the housing will be automatically adjusted to the direction of pull of the load suspending line or cable.

15 Further objects of the invention reside in the details of construction of parts, and in their relationship and mode of use, as will hereinafter be fully described.

20 In accomplishing these and other objects of the invention, I have provided the improved details of construction the preferred forms of which are illustrated in the accompanying drawings, wherein—

25 Fig. 1 is a side view of a fairleader embodying the improvements of the present invention therein.

Fig. 2 is a front end elevation of the same, indicating in dotted lines the lateral turning of the housing in accordance with change in direction of the load line.

30 Fig. 3 is a cross-section taken on line 3—3 in Fig. 1.

Referring more in detail to the drawings—

35 It is anticipated that a fairleader of the present kind shall be used at the outer ends of a boom mounted on a mobile vehicle such as, for example, a tractor of crawler track type. Also that the booms be so mounted that it can be swung from side to side on the tractor. The specific form or construction of the boom and the means by which the fairleader is secured thereon forms no particular part of the present invention. However, in Fig. 1 I have indicated the outer 40 end portion of the boom by reference numeral 10 and have shown my present preferred means for and method of securing the fairleader thereto.

50 The fairleader of the present invention comprises a housing, designated in its entirety by

reference numeral 12, formed at one end with a cylindrical mounting stem, or hub 13 that is shown to be integrally cast with the housing. The housing comprises opposite side walls 14—14', that are rigidly joined in spaced relationship along their top edges by a web or wall 15 preferably welded thereto.

The cylindrical stem portion 13 of the housing is coaxially disposed and rotatably mounted within a supporting bearing 18 of tubular, or cylindrical form. Antifriction bearings may be employed between the parts if so desired. I have shown the outer end of the part 13 to be fitted with a collar 19 secured by welding 20, securing the housing yet providing a free swiveling action about the axial line of the stem.

The tubular bearing 18 is formed at one end with an encircling flange 22 and this is rigidly secured by bolts 23, or otherwise fixedly secured to the boom end plate 24. The arrangement of the bearing 18 on the boom is such that operating lines or cables passing outwardly along the boom from its mounting end can be extended substantially in parallel relationship, as seen in Fig. 1, through the tubular mounting stem 13 of the housing, for guided travel over flanged guiding sheaves located between the side walls of the housing in the tandem arrangement indicated.

In the present arrangement, I employ a "load carrying" line 25 and a "closing line" 26. The cable 25 passes through the tubular stem parallel with its axial line, but downwardly offset therefrom, and then passes over and downwardly from a supporting sheave wheel 27 that is revoluble on a supporting pin or shaft 28 that is extended through the opposite side walls of the housing. The closing line 26 extends through the tubular stem 13 substantially coincident with its axial line, and beyond the wheel 27, and passes over and downwardly from a sheave wheel 30 supported between the side walls of the housing on a pin or shaft 32. The outer end of cable 25 will be connected in the usual way to the grapple, bucket or other device used. The closing line 26, likewise, would be connected to the grapple for opening or closing it in the usual way. The cables extend along the boom from suitable cable winding drums or winches on the tractor.

It is a feature of this invention that the axis of the sheave wheel 27 is offset substantially below the axial line of the supporting stem 13 of the housing. Therefore, a load as suspended by the cable 25 from the housing will cause the latter to automatically rotatably adjust itself in the bearing 18 to maintain its alignment with the load line. The closing line, being connected with the grapple or load, will move therewith and thus will be caused to maintain a relationship to the housing corresponding to that of the load line.

With the parts so arranged, it is readily apparent that when a bucket, grapple or other similar device, is suspended from a boom and utilizes two lines passing through the fairleader housing

as herein shown, the swinging of the load from side to side coincident with the paying out or hauling in of the cables will not result in chafing of the cables. This is by reason of the fact that the housing turns on its axis and automatically maintains alignment with the load cable. Actual test over a considerable period of time has proven that wear on cables from this cause is practically eliminated.

The present arrangement of lines as passing from the housing avoids chafing on each other. Operating speed can be increased and lines may be paid out or drawn in while the boom is being swung from side to side, with no detrimental effects on the lines.

Having thus described my invention what I claim as new therein and desire to secure by Letters Patent, is:

1. A loading boom equipped at its outer end with a fairleader including a housing having a tubular mounting hub extending longitudinally from its inner end and said boom having at its outer end a tubular bearing mounting said hub for axial oscillation, the housing comprising oppositely disposed spaced side walls, two sheave wheels on the housing between the side walls thereof disposed one in advance of the other in a longitudinally extending central vertical plane common to the axis of the mounting hub and said housing, supporting axles for said sheaves mounted on the housing below the level of the longitudinally extending axial line of the mounting hub, and two cables each extending along the boom and through said hub and over one of said sheave wheels, said sheave wheels supporting the cables spaced from each other and in spaced relation with the mounting hub and the side walls of the housing.

2. The construction recited in claim 1 and wherein one of said sheave wheels has its top peripheral portion disposed to support the cable associated therewith to extend through the mounting hub to said sheave wheel along the axial line of the mounting hub, the other sheave wheel having its top peripheral portion disposed to support the other cable to extend through the mounting hub to said sheave wheel in a line below and substantially parallel with the axial line of the mounting hub.

MARC D TROYER.
